UNITED STATES PATENT OFFICE.

LEONARD S. COPELIN, OF SEAL BEACH, CALIFORNIA.

ROTARY MUD.

1,411,164.

Specification of Letters Patent. Patented Mar. 28, 1922.

Application filed August 5, 1921. Serial No. 490,170.

To all whom it may concern:

Be it known that LEONARD S. COPELIN, a citizen of the United States of America, residing at Seal Beach, in the county of 5 Orange and State of California, has invented new and useful Improvements in Rotary Muds, of which the following is a specification.

The object of the invention is to provide 10 an efficient and comparatively inexpensive material for and method of sealing driven or drilled wells for oil, gas and the like in strata which is of crumbling or loose formation or has a tendency to cave, as a means of 15 maintaining an unobstructed passage and of excluding or preventing the inflow to the well or hole of undesirable liquids or other products tending to contaminate the product for which the well is designed and 20 for which purpose it has been the practice to use a mud, referred to in the art as a rotary mud, of a clay consistency which is objectionable by reason of being 25 difficult to handle or apply, of being readily affected by oil or other liquid products of the well, of absorbing oil which when deposited in small quantities is rendered 30 difficult of detection, which is more or less permeable from the outside by liquids or 35 gases which it may be the desire to exclude and the like; and therefore it is the particular object of the invention to provide a rotary mud or sealing material which by reason of being of a radically different specific 40 gravity from that of soil, sand, rock, drillings and the like is readily distinguishable and separable therefrom by precipitation of the latter, which has the property of being 45 readily applied to the portions of the walls 50 of the hole or well which are to be sealed, which is of a cohesive property and a colloidal texture adapting it to form not only 55 a wall adhesive but an aggregative of the loose particles of soil and rock incidental to a caving condition, which is repellent to 60 oil and practically impermeable by water and similar liquids.

In the drawings, in which the means for carrying out the method is conventionally illustrated, Figure 1 is a view partly in elevation and partly in section of a conventional well boring apparatus; and Figure 2 is a sectional view of the walls of a well hole illustrating the solidifying effect of the use of a rotary mud.

The usual drill bit 1 is employed and carried at the lower extremity of the tubular drill rod 2, the latter being surrounded by the tubular casing 3 that is lowered behind the drill bit and forms the well tube when 60 the oil or gas area has been reached. If the hole or shaft being drilled shows a caving tendency the rotary mud is introduced through the drill rod 2, entering the hole in the vicinity of the bit 1 and being a calcium carbonate preferably in the form of 65 waste or refuse lime which is a by-product of the manufacture of sugar, is applied to the walls of the well by the operation of the drill, filling the interstices of the wall and 70 serving as a binder for loose particles of soil and rock. This particular material is of special advantage in this connection; first, because, being of a less specific gravity than rock and rock filings or cuttings, the 75 particles of the latter readily separate and precipitate; second, because the said material is of a cohesive nature and colloidal texture adapting it to penetrate the interstices or pores of the rock and soil and 80 forms a plaster which keys itself to the material and at the same time anchors the loose particles thereof; and third, because the said material is not only repellent to oil but is 85 impermeable to water except to a very slight degree and constitutes a barrier to exclude moisture and liquids in strata which are productive of undesirable materials tending to contaminate the product for which the well is designed.

In Figure 2, at 4, there is shown the effect of the use of the rotary mud in the manner above described.

The lime mud has not the property of setting or becoming hard but remains permanently plastic and constitutes a permanent barrier which is not readily attacked by liquids in the excluded strata. The mud is removed from the exposed strata by the ordinary washing method.

The objection to clay and like rotary muds, in addition to the unsubstantial characteristics thereof is that they are readily absorptive of oil so that if the operation involves prospecting for oil, and the latter 105 appears in very small quantities, the tests may fail to show any trace thereof if a rotary mud of the ordinary type is employed, whereas with the rotary mud of calcium carbonate the oil will appear in small globules 110

in the samples withdrawn ordinarily at intervals from the hole as the drilling proceeds, and therefore constitutes a safe and reliable guide to the driller as to the ultimate yield of the well.

In applying the lime as a rotary mud a further advantage resides in the fact that it is at first readily absorptive of water to form a thick plastic mass which can readily 10 be worked by the drill in forming a coating of cement to anchor loose and caving portions of the wall of the hole.

Having described the invention, what is claimed as new and useful is:—

15 1. The method of solidifying soil in wells and other shafts which consists in the injection of a calcium carbonate in the interstices of caving or loose portions.

2. The method of solidifying soil in wells 20 and other shafts which comprises the appli-

cation of waste or refuse lime to caving or loose portions of the walls.

3. The method of solidifying soil in wells and other shafts which comprises the application to caving or loose portions of the walls 25 thereof of waste or refuse lime constituting a by-product of the manufacture of sugar.

4. The method of solidifying soil in wells and other shafts showing a caving tendency which consists in introducing into the well 30 or shaft waste or refuse lime which is a by-product of the manufacture of sugar, and thereafter applying the same to the walls by operation of the drill to fill the interstices 35 of the wall and serve as a binder for loose particles of soil in rock.

In testimony whereof he affixes his signature.

LEONARD S. COPELIN.
